(57) **CLAIM**

The ornamental design for a barbecue grill toy, as shown and described.

DESCRIPTION

FIG. 1 is a rear, bottom, left perspective view of my design for a barbecue grill toy;

FIG. 2 is a front, top, right perspective view thereof;

FIG. 3 is a front elevation view thereof;

FIG. 4 is a rear elevation view thereof;

FIG. 5 is a left elevation view thereof;

FIG. 6 is a right elevation view thereof;

FIG. 7 is a top plan view thereof;

FIG. 8 is a bottom plan view being thereof; and,

FIG. 9 is a front, top, right perspective view of the barbecue grill toy in a closed configuration.

The broken lines in the drawings depict portions of the barbecue grill toy that form no part of the claimed design.
